UNITED STATES PATENT OFFICE

SYLVESTER A. JOHNSON, OF NORTH PROVIDENCE, RHODE ISLAND, ASSIGNOR TO SPEIDEL BROS., OF PROVIDENCE, RHODE ISLAND, A FIRM COMPOSED OF EDWIN F. M. SPEIDEL AND ALBERT E. R. SPEIDEL, BOTH OF EDGEWOOD, RHODE ISLAND

CLASP

Application filed January 30, 1929. Serial No. 336,265.

This invention relates to a clasp of the type which is especially adapted to secure together two parts of a ribbon band or bracelet used for securing a wrist watch to the arm of the wearer; and has for its object to provide a clasp which shall be positive in its operation and of ornamental appearance and yet be of a construction inexpensive to manufacture.

A further object of the invention is to provide a construction which may be formed by a minimum number of foot press operations and one which will be light in weight although employing sufficient amount of material to completely conceal the resilient spring used for snapping the parts together.

A still further object of the invention is the provision of a construction in which the securing means and its housing may be always of the same size to be utilized with varying widths of clasps for different widths of ribbon bands.

With these and other objects in view, the invention consists of certain novel features of construction, as will be more fully described, and particularly pointed out in the appended claims.

In the accompanying drawings:

Fig. 1 is a top plan view of the clasp and a portion of ribbon secured thereby.

Fig. 2 is a perspective view of the sheet metal frame plate of the socket member.

Fig. 3 is a perspective view of the blanked out housing member.

Fig. 4 is a perspective view of the housing member bent into box or trough shape.

Fig. 5 is a top plan view of the housing member of Fig. 4.

Fig. 6 is a perspective view of the spring member.

Fig. 7 shows the spring within the housing member.

Fig. 8 shows the housing member and plate member in assembled position looking at one side thereof.

Fig. 9 is a perspective view of the socket member before the arms or extending portions of the housing member are bent over the opposite side of the plate from that shown in Fig. 8.

Fig. 10 is a section on line 10-10 of Fig.

9, the arms or extending portions being bent over to engage the opposite side of the plate.

Fig. 11 is a section on line 11-11 of Fig. 10.

Fig. 12 is a section of the stud member.

Fig. 13 is a sectional view showing the stud member and socket member in clasped relation.

In the use of ribbon bands for securing a wrist watch in position on the wrist of the wearer, it is desirable to provide a clasp comprising stud and socket members, one of which may be secured to an end of the ribbon and the other adjustably secured along the strap so that it may assume different positions to accommodate wrists of different sizes; and in order to provide such a construction of sheet metal which shall be light in weight and yet be strong and durable and handsome in appearance, I have provided a construction which can be made by the minimum number of foot press operations, to blank and bend sheet stock into suitable form to strengthen it and conceal and retain a separate tempered spring in place; and the following is a detailed description of the present embodiment of this invention illustrating the preferred means by which these advantageous results may be accomplished:

With reference to the drawings, the socket member consists of a sheet metal frame plate member 15, which may be cut from sheet stock into the shape illustrated in Fig. 2, having slots 16 adjacent its ends of a width to receive a ribbon 17 woven in and out of the slots to adjustably secure the same thereto. An intermediate slot 18 is formed between the two ribbon slots 16 to receive a portion of the stud member, as will be presently described.

The socket member is also provided with a housing part 19 which is blanked out, as illustrated in Fig. 3, and bent into trough or box form, as illustrated in Fig. 4, having an outer wall 20, side walls 21 and end walls 22, each of the latter of which has a reduced extending portion or arm 23 to pass through notches 24 in the sides of the frame plate member 15, to be folded over the opposite side of the plate to secure the housing member thereto, with its side and end walls snugly

abutting one of the surfaces of the plate as is clearly apparent from the illustration.

The outer wall 20 of the housing member is slotted as at 25 to substantially register with the slot 18 in the frame plate and a 5 U-shaped spring 26, having a pair of arms 27, is confined within the housing member between its outer wall 20 and the frame member and held in the desired position by the 10 end and side walls of the housing so as to resiliently engage the projecting portion 28 of a stud member extending from a top metal plate 29 to frictionally and resiliently hold the stud and socket members in clasped position.

15 The projection has an enlarged head 30, as will be clearly apparent from Fig. 13, so as to offer greater resistance to the separation of the stud and socket members when in 20 clasped position. The projection 28 is set into a recess 31 in the plate 29 and held therein by any suitable means such as solder 32.

25 Various widths of stud and socket plate members are made, for different width ribbons, but by the construction shown the identical same size of housing may be used regardless of the different widths of stud and socket plates by notching the frame plate to the desired depth so that the space left between the notches will always be the same dimension.

30 It will also be apparent that this housing member completely conceals the spring which is unsightly from an artistic standpoint in an article of jewelry of this character, while the bending of the housing into the trough, 35 box or channel shape illustrated adds sufficient strength to the same so that it may be made of very thin, light stock and yet be sufficiently strong to withstand any abuse to 40 which it is ordinarily subjected.

45 The foregoing description is directed solely towards the construction illustrated, but I desire it to be understood that I reserve the privilege of resorting to all the mechanical changes to which the device is susceptible, the invention being defined and limited only by the terms of the appended claims.

I claim:

50 1. A clasp comprising a plate member having a slot to receive a ribbon, a stud having an enlarged head projecting therefrom, a second plate member having a pair of spaced slots to adjustably receive a ribbon, a trough-shaped housing member of a width less than the distance between said slots secured to said plate member between said slots, a generally U-shaped spring confined within the space between said housing member and plate, and a slot in said housing to receive said stud when inserted therethru.

55 2. A clasp comprising a stud member and a socket member, each adapted to be secured to a ribbon band, said socket member comprising a flat sheet metal frame having

notched side edges, a trough-shaped sheet metal housing member at one side of said frame, portions on said housing member extending through the notches and over the opposite side of the frame to lock the housing member and frame in assembled relation to form a housing, and a spring within said housing and engaged by said frame and said housing member whereby the movement of said spring is limited to a lateral displacement, said housing member having an entering slot to receive part of said stud member.

70 3. A clasp comprising a plate member having a slot to receive a ribbon, a stud having an enlarged head projecting therefrom, a second plate member having a pair of spaced slots to adjustably receive a ribbon and an intermediate slot, a trough-shaped housing member having an outer wall and side and end walls covering said intermediate slot, said outer wall being spaced from said plate and slotted to register with said intermediate slot, a generally U-shaped spring confined within the space between said housing member and plate member and in a position to resiliently engage said stud when inserted through said slots to retain it therein, said second plate having notches on its side edges and said side walls of said housing member having extending portions to pass through said notches and engage the opposite side of said plate member to hold said member in position.

75 4. A clasp comprising a stud member and a socket member, each adapted to be secured to a ribbon band, said socket member comprising a flat sheet metal frame having notched side edges, a trough-shaped sheet metal housing member at one side of said frame, arms on said housing member in said notches and extending over the opposite side of the frame to lock the housing member and frame in assembled relation, a spring within said housing, and said housing having an entering slot to receive a part of said stud member.

80 In testimony whereof I affix my signature.
SYLVESTER A. JOHNSON.
